UNITED STATES PATENT OFFICE.

SAMUEL CLAUDE JOHNSTON, OF LANCASTER, SOUTH CAROLINA.

KNOCK-OFF MECHANISM FOR LOOMS.

1,353,343.

Specification of Letters Patent. Patented Sept. 21, 1920.

Application filed March 8, 1920. Serial No. 363,948.

To all whom it may concern:

Be it known that I, SAMUEL CLAUDE JOHNSTON, a citizen of the United States, residing at Lancaster, in the county of Lancaster and State of South Carolina, have invented certain new and useful Improvements in Knock-Off Mechanism for Looms, of which the following is a specification, reference being had to the accompanying drawings.

This invention relates to looms, and particularly to stopping or "knock-off" mechanism for looms.

The general object of the invention is to obviate the difficulty now experienced with looms when the woven cloth starts to wrap on the sand roller or take-up roller, which is liable to break the intermediate gear bracket and change gear bracket.

More specifically, the object of the invention is to provide means for automatically operating the knock-off or shipper lever of the loom when there is too much friction on the sand roller or take-up roller caused by the wrapping of the cloth on the sand roller.

And a further object is to provide a very simple mechanism to this end which may be readily applied to any ordinary loom, but which is particularly adapted for a Draper loom.

A further object is to provide the member which drives the sand or take-up roller, which is shiftable under undue strain, and which, when shifted, will act to shift the shipper lever and cause the loom to knock off.

A further object is to provide a device of this character which includes a worm slidably mounted upon a drive shaft and engaging a worm wheel, which worm wheel is engaged through intermediate gearing with the sand or take-up roller, the worm being held in engagement with the worm wheel by means of a spring, and provide in connection with this shiftable worm a lever operatively connected to the stop motion arm of usual character, which is in turn connected to the shipper lever so that when the cloth starts to wrap on the take-up roller, it exerts such friction on the take-up roller as to stop it or retard it. This stoppage causes the worm to shift along the shaft against the action of the spring and thus shift said lever, which in turn operates the arm to shift the shipper lever to a position

to shift the bolt on the loom to cause the loom to knock off.

Other objects will appear in the course of the following description.

My invention is illustrated in the accompanying drawings, wherein:—

Figure 1 is a rear elevation of one end of a loom having my improved take-up roller actuating mechanism applied thereto; 65

Fig. 2 is a front fragmentary elevation of a loom showing my take-up actuating or knock-off mechanism applied thereto;

Fig. 3 is a view of the worm shaft 10 with the worm thereon in section; 70

Fig. 4 is a perspective view of the sleeve surrounding the worm carrying shaft;

Fig. 5 is a perspective view of the lever therefor;

Fig. 6 is a fragmentary perspective view 75 of the arm 35.

In these drawings, I have illustrated such portions of a Draper loom as are allied with my stopping mechanism. It will be understood that the drawings are purely illustrative and are only sufficient to indicate the position and operation of my improved mechanism. I have illustrated in these drawings a continuous take-up motion, but I do not wish to be limited to this, as my invention equally well applies to an intermittent take-up motion.

In these drawings, 10 designates a horizontally disposed shaft at the side of the loom which carries at one end the beveled gear wheel 11 mounted in suitable bearings 12. This beveled gear wheel meshes with a driving beveled gear wheel 13. The other extremity of this shaft 10 is reduced in diameter and carries upon it a slidably mounted worm gear 14. This worm gear meshes with a worm gear wheel 15 mounted in suitable bearings 16 and having at one extremity the gear wheel 17 shown as meshing with a relatively large gear wheel 18 which carries a pinion 19 meshing with a relatively small gear wheel 20 carrying a small pinion 21, in turn meshing with a relatively large gear wheel 22, which in turn meshes with or is operatively engaged 100 with a pinion 23 carried by the shaft of the sand roller or take-up roller 24. It will be understood, of course, that the cloth roller is intended to be operatively driven from one of these gear wheels. The number of these intermediate gear wheels is immaterial to my invention, and my invention is

not connected in any way with the manner in which the cloth roller is driven or the manner in which the sand roller or take-up roller is driven.

- 5 As before remarked, the worm 14 is slidably mounted upon the shaft 10, and one end bears against a cap nut 25. Bearing against the other end of the worm 14 is a sleeve 26 having parallel, annular flanges to define an 10 annular recess receiving a ring 27 like a shipper ring, this ring having the rearwardly projecting stud 28. Bearing against the end of the sleeve 26 opposite the worm 14 is a spring 29, which in turn bears against 15 a collar 30 fastened by a set screw 31 to the reduced portion of the shaft 10.

It will now be obvious that the worm may be shifted toward the left in Fig. 1, thus shifting the sleeve 26 against the 20 action of spring 29, and that when the pressure is released, the spring 29 will cause the parts to return to their normal positions.

Pivoted to any suitable portion of the frame is a lever 32 whose upper end is perforated for the passage of the stud 28. The lower end of this lever has pivoted to it a slotted link 33. Mounted upon a shaft 34 is the usual arm 35. This shaft 34 is connected to the ordinary stop motion mechanism of the loom. The upper end of this arm 35 is formed with a horizontally disposed loop or yoke 36 which engages over the lower end of the usual shipper lever 37, which is operatively connected to the belt 35 shifting means in the usual manner. A pin 38 extends from the arm 35 into the slot of the link 33. The slotted link 33 permits the arm 35 to be operated in one direction to knock off the loom without affecting the lever 32, but when this lever 32 is operated by a shifting of the worm, as will be described, it will shift this arm 33 to cause the yoke 36 to operate on the shipper lever 37 to thereby knock off the loom.

40 45 In the operation of this mechanism, when the sand roller stops or hangs up by reason of the cloth wrapping around the latter, the friction on the sand roller will impede its movement so that the gear 15 will not rotate as fast as the worm, and as a consequence the resistance will cause the worm to shift on the shaft 10 in the direction of the arrow, Fig. 1, against the action of the spring 29. This movement of the worm will cause the lever 32 to shift the stop motion arm 35 in a direction to shift the shipper lever out of its holding notch and cause the loom to stop.

It is to be understood that in the drawings above referred to, I have not attempted to illustrate all the mechanism of the Draper loom, but have simply shown those parts with which my attachment is intimately connected. While I have heretofore referred to 60 and illustrated a continuous take-up motion,

I do not wish to be limited to this, as it is obvious that a step by step take-up motion may also be used.

I claim:

1. In a loom, a take-up roller, mechanism 70 for driving the take-up roller including a driven member operatively connected thereto and a driving member operatively engaged with the driven member, said driving member being yieldable in one direction when the motion of the driven member is impeded, a lever operatively connected to the driving member and shiftable therewith, a knock-off arm having a yoke, a shipper lever passing through said yoke and operated thereby, a lever operatively connected at one end to the driving member and shiftable therewith, the opposite end of the lever having a link operatively connected to said knock-off arm. 80

2. In a loom, a take-up roller, mechanism for driving the take-up roller including a worm gear wheel operatively connected to the take-up roller, and a driving shaft, a worm slidably mounted upon the driving 90 shaft and engaging said worm gear wheel, a spring normally holding said worm from longitudinal movement on the driving shaft and holding it in engagement with the worm gear wheel, a knock-off mechanism, and 95 means operatively connecting the worm with said knock-off mechanism to cause an operation of the knock-off mechanism when the worm slides on the shaft against the action of said spring under the resistance of 100 offered by the worm gear wheel.

3. In a loom, a take-up roller, mechanism for driving the take-up roller including a worm gear wheel operatively connected to the take-up roller, and a driving shaft, 105 a worm slidably mounted upon the driving shaft and engaging said worm gear wheel, a spring normally holding said worm from longitudinal movement on the driving shaft and holding it in engagement with the worm gear wheel, a knock-off arm having a yoke, a shipper lever passing through the yoke, and means operatively connecting the worm to the knock-off arm to cause the 110 operation of the knock-off arm upon a sliding movement of the worm due to undue resistance of the worm wheel to rotation. 115

4. In a loom, a take-up roller, means for driving the roller including a worm gear wheel operatively connected to the roller, a 120 driving shaft therefor, a worm engaging the worm gear wheel and slidably mounted on the shaft for movement in one direction when the worm gear wheel resists rotation, a sleeve bearing against the worm, a spring 125 bearing against the sleeve and surrounding the shaft, a lever pivoted intermediate its ends and at its upper end having rotative engagement with the sleeve, a knock-off arm having a yoke, a shipper lever passing 130

through the yoke, and a slotted link pivotally connected to the lower end of the lever, the knock-off arm having a pin passing through the slot of the link.

- 5 5. In a loom, a take-up roller, driving means for the take-up roller including coacting driving and driven rotatable gear elements meshing with each other, the driving gear element being yieldably held in operative engagement with the driven gear element but being shiftable out of operative position upon resistance being offered by the driven gear element, and means operatively connecting the driving element to the knock-off mechanism of the loom and actuating the knock-off mechanism when the driving element is shifted by resistance to its movement offered by the driven element.

6. In a mechanism of the character described, a driving shaft having thereon a worm slidably mounted on the driving shaft, a worm wheel with which the worm engages, a spring urging the worm into a position where it is engaged with the worm wheel, said mechanism permitting the worm to automatically shift out of operative engagement with the worm wheel upon resistance being offered to the movement of the worm wheel, and controlling means shifted into operative position by the shifting of said worm out of operative engagement with the worm wheel.

In testimony whereof I hereunto affix my signature.

SAMUEL CLAUDE JOHNSTON.
